HERMAN R. HARRIGAN, OF SOUTH HADLEY, MASSACHUSETTS, ASSIGNOR TO AMERICAN WRITING PAPER COMPANY, OF HOLYOKE, MASSACHUSETTS, A CORPORATION OF NEW JERSEY.

FOURDRINIER-WIRE SCREEN.

Application filed May 18, 1922. Serial No. 561,877.

This invention relates to an improved Fourdrinier wire screen for use in paper making machines and has for its object the incorporation in such a screen, of means for watermarking the paper during the process of its manufacture.

The common practice heretofore for watermarking paper, has been by means of a dandy roll rotating in contact with the surface of the paper being carried upon the Fourdrinier wire, which dandy roll usually carries a screen with appropriate markings therein for varying the density of the paper at certain portions thereof during its manufacture. The use of such dandy rolls for watermarking paper is confined to papers of the better grade, for the reason that the action of the dandy roll requires that the paper be run through the machine at a slow rate of speed as compared with the speed of running the machine in the manufacture of cheaper papers.

In order therefore, to enable paper manufacturers to watermark their cheaper grades of papers with some appropriate mark which will identify their product, I have devised means which can be incorporated directly in the Fourdrinier making wire for causing the variable density in the paper above described, and which will not in any way limit the speed in which the machine can be run in the making of cheap paper.

The idea thus conceived may be carried out in different ways by varying the weave of the Fourdrinier wire fabric so as to create zones therein of different drainage capacity for the removal of the moisture of the pulp. As is well known, the density of the different portions of the paper being formed on the screen will be varied in accordance with the greater or less drainage capacity at different portions of the making screen, and in creating such zones of different drainage capacity on the Fourdrinier wire screen, the object is merely to vary the drainage enough to watermark the paper and without appreciably weakening its strength at said watermarked portions. As before stated, the creation in the Fourdrinier

wire screen of such local areas of greater or less drainage may be accomplished by a sufficient variation in the weave of said Fourdrinier screen. More elaborate figures for watermarking paper may be incorporated in the Fourdrinier wire screen by weaving the same in pattern controlled or Jacquard looms. For illustrating the broad idea of the invention, I have shown a few simple forms of changing the weave in said Fourdrinier wire sufficient to create the local zones of different drainage capacity which will result in watermarking the paper during its making.

Referring to the drawings which show such a simple embodiment of the invention—

Fig. 1 is a plan of a portion of a Fourdrinier wire screen in which at intervals the weft wires and the warp wires are spaced farther apart than the normal spacing of said wires in the body of the fabric;

Fig. 2 is a detail section enlarged of a portion of said fabric showing the formation of the paper thereon;

Fig. 3 is a plan of a portion of a Fourdrinier wire screen showing another method of changing the weave therein in which, at intervals throughout, is incorporated a much heavier weft wire and a much heavier warp wire than the main wires of the fabric;

Fig. 4 is a detail section enlarged showing the paper being formed on the wire screen of Fig. 3;

Fig. 5 is a plan of still another form of a Fourdrinier wire screen in which at intervals throughout, the warp wires are spaced farther apart than the normal spacing of said wires and in which at intervals heavier warp wires and heavier weft wires than the main wires of the fabric are incorporated;

Fig. 6 is an enlarged section of paper being formed on the wire of Fig. 5.

Referring more particularly to the drawings, the main warp wires with which the Fourdrinier wire fabric is woven is indicated at 1 and the weft wires at 2. In the weaving of the fabric shown in Fig. 1, the weft wire has been omitted at intervals to

create spaces 3 and 4 and at intervals the warp wires have likewise been omitted to create spaces 5, 6 and 7 as shown.

The Fourdrinier wire screen in Fig. 1 will therefore have at the spaces 3, 4, 5, 6, and 7 a greater drainage capacity for removing the water from the pulp in the formation of the paper than the closer mesh in the main body of the fabric. The intersection of the spaces 3 and 4 with the spaces 5, 6, and 7 which are indicated at 8, 9, 10, 11, 12 and 13 will have a still greater drainage capacity as will be obvious. The paper being formed on such a Fourdrinier wire screen as shown in Fig. 1 will consequently be thicker at the spaces above indicated and will be less impervious to light at these local zones, thus giving what is known as a watermark to the paper. In Fig. 2, an attempt is made to illustrate the different density of the paper as it is formed on the wire screen of Fig. 1. The paper or pulp indicated at P will be drawn through the screen to a slightly greater extent at the zone space 5 than through the close mesh of the remainder of the screen, and thus result in being more thickly formed at this area.

In Fig. 3 I have shown heavier warp wires 14 and heavier weft wires 15 woven into the fabric at spaced intervals, and by heavier wires, I mean, heavier than the main warp and weft wires of said Fourdrinier wire screen. The employment of such heavier warp and weft wires will produce a slightly less drainage capacity for the fabric at the areas adjacent said heavier wires which will result in the paper being formed of slightly less density at said areas. By reference to Fig. 4 which shows a section of the paper being formed on the wire screen of Fig. 3 it will be observed that the paper is thinner or of slightly less density adjacent the heavy wire 14 than above the other wires of said fabric, due to the decreased drainage capacity of said fabric adjacent said heavier wires.

Fig. 5 illustrates a Fourdrinier wire making screen which embodies a combination of the means shown in Figs. 1 and 3 for varying the drainage capacity of said making wire. In this view the weft wires 1 are spaced apart at intervals to form the spaces 5 and 7 for increasing the drainage capacity at such areas, and heavier warp wires 14 and heavier weft wires 15 are likewise woven into the fabric at intervals to decrease the drainage capacity of the fabric adjacent said heavier wires.

Fig. 6 illustrates the formation of the paper on such a making wire as shown in Fig. 5 wherein it will be seen that the paper is formed slightly thinner adjacent the heavier warp wire 14 and slightly thicker in the space area 5 between the normal warp wires 1.

It will be obvious to those skilled in the art that the paper made on the Fourdrinier wire fabric of Figs. 1, 3, and 5 will be formed with a different density at certain zones which will not ordinarily be observable in the paper unless the same is held to the light, in which case, there will be exhibited a plaid-like marking in the paper of the same nature as a watermark heretofore formed by a dandy roll. Inasmuch as the making wire has incorporated directly in it the means for thus watermarking the paper, it may be used in the paper making machine in the same manner as the ordinary Fourdrinier wire screen and can be run at the desired speeds for the making of both cheap and better grade papers.

In other words, a Fourdrinier wire screen of this character may be employed to watermark any paper made thereon and its speed of operation in the paper making machine is not in any way limited by the feature of having incorporated therein means for watermarking the paper. The value of this improvement will be appreciated by all paper manufacturers who desire to watermark their cheaper grades of paper and have heretofore found it impossible to do so by reason of the difficulty in employing a dandy roll when the paper making machine is run fast enough to get the production necessary for cheap paper. It has been found that in attempting to use a dandy roll for watermarking paper on a making screen run at high speed in the production of cheap papers, the dandy roll rolling in contact with the paper pulp on the making screen does not have time to function properly for watermarking the paper, and moreover, has a tendency to pull the pulp off the making screen. Such difficulties are avoided by the use of a making screen in which the means for watermarking the paper are incorporated directly in the making screen as heretofore described.

What I claim is:

1. A Fourdrinier woven wire fabric for paper making having means incorporated therein for watermarking paper during the making of the paper which means comprises watermarking portions formed in said wire fabric to vary the density of the paper to be formed at said watermarking portions sufficiently to watermark said paper without weakening the strength of the paper at said portions.

2. A Fourdrinier woven wire fabric for paper making having means incorporated therein for watermarking paper during the making of the paper which means comprises watermarking portions formed in said wire fabric by varying the weave thereof at said portion so as to vary the density of the paper to be formed at said watermarking portions sufficiently to watermark said paper with-

out weakening the strength of said paper at the main body of said wire fabric so as to said portions. vary the density of the paper to be formed 10

3. A Fourdrinier woven wire fabric for paper making having means incorporated 5 therein for watermarking paper during the making of the paper which means comprises watermarking portions formed in said wire fabric of closer or more open mesh than the main body of said wire fabric so as to vary the density of the paper to be formed 10 at said watermarking portions sufficiently to watermark said paper without weakening the strength of said paper at said portions.

In testimony whereof I have affixed my signature.

HERMAN R. HARRIGAN.
